WIRE HELMET GUARD

Terry A. Litsinger, Sr., 905 Mae St.,
Kent, Ohio 44240

Filed Oct. 12, 1972, Ser. No. 296,767

Term of patent 14 years

Int. Cl. D2—03

U.S. Cl. D2—232

FIG. 1

FIG. 2

FIG. 3

FIG. 4

FIG. 1 is a top plan view of a wire helmet guard, showing my new design.

FIG. 2 is a side elevational view thereof.

FIG. 3 is a front elevational view; and

FIG. 4 is a second embodiment of the design of FIG. 1.

I claim:

The ornamental design for a wire helmet guard, as shown and described.
